UNITED STATES PATENT OFFICE.

GEORGE J. HEYMOSS, JR., OF DETROIT, MICHIGAN.

HORSESHOE PAD.

Application filed October 6, 1924. Serial No. 741,884.

My invention relates to an improved horseshoe pad.

The object is to provide a horseshoe pad adapted to serve as a cushion for the shoe and having a ground-engaging metal plate so supported on edge as to make for a particularly secure and good footing on the pavement and designed primarily for use on slippery and icy pavements.

10 An important feature is the provision of such a pad having a yielding portion to support the ground-engaging plate below the surface of the pad so that the plate strikes the ground before the shoe which is carried by the pad. This plate is so supported on edge that the toe of the plate first engages the ground, the plate being adapted to swing slightly about its support to bring the heel thereof into engagement with the 20 ground.

The pad itself is of suitable cushioning material such as rubber and has a marginal horseshoe supporting portion, an integral heel portion and a loop-shaped ledge portion extending forwardly from the heel within the shoe, and a ground-engaging plate surrounding the ledge and supported thereby at the toe below the surface of the pad and in such a manner that the toe first strikes the ground, said plate adapted to swing about its point of connection with the ledge to permit the heel to strike the ground, and a support for the plate adapted to yield under pressure to permit the toe 30 of the plate to bear against the surface of the pad.

The above objects and others together with the details of construction of my improved horseshoe pad will more fully appear from the following description of the 40 illustrative embodiment of my invention shown in the accompanying drawings and defined in the claims.

In the drawings,—

45 Figure 1 is a plan view of my improved pad with a horseshoe attached,

Fig. 2 is a sectional view taken on line 2—2 of Fig. 1, and

50 Fig. 3 is a perspective of the pad with the horseshoe and plate removed.

55 My improved horseshoe pad is formed of suitable cushioning material such as rubber and is provided with a flat marginal portion 5 adapted to serve as a support for a horseshoe 6. The pad has an integral heel portion 7 which projects below the surface

of the pad and there extends forwardly from this heel portion a loop-shaped ledge 8 of somewhat the same general shape as the horseshoe and positioned within the 60 horseshoe and substantially smaller than the shoe. This construction is shown clearly in Fig. 3.

Reference is hereby made to applicant's Patent No. 1,496,414, dated June 3, 1924, 65 relating to a horseshoe pad which possesses certain characteristics in common with the one here described.

In association with the pad structure above set forth I provide a plate 9 adapted 70 to surround the ledge 8 and secured thereto in a suitable manner such as by means of bolts 10 which extend through the ledge and through the plate to support the toe of the plate below the surface of the pad and 75 at such a height that the toe of the plate will strike the ground before the toe culk 11 of the shoe 6 and also before the heel 12 of the plate engages the ground. When my improved device is in use the toe portion of 80 the plate 9 first strikes the ground. This occurs before the toe of the horseshoe engages the ground and before the heel portion of the plate engages the ground. The plate 9 is supported by the ledge 8 of the 85 pad which ledge is formed of the same structure as the pad, such as rubber, and this ledge yields under the pressure brought to bear upon it by the plate engaging the ground. The plate swings slightly about its 90 connections 10 with the ledge so that the heel portion of the plate is brought into contact with the ground following its engagement by the toe portion of the plate. This position is shown in dotted outline in 95 Fig. 2. Due to the yielding character of the ledge the toe portion of the plate moves toward the base of the pad and the plate is provided at the toe with a base flange 14 adapted to engage the flat base portion of 100 the pad.

The ledge 8 of the pad extends forwardly from the heel to such a distance that the toe of the plate 9 is supported forwardly of the 105 frog of the horse's foot.

My improved horseshoe pad when used as described operates to make a very secure footing and is particularly easy on the horse's foot.

What I claim is:

1. The combination with a horseshoe, of a pad to support the shoe, said pad provided

with a plate set on edge and having a toe portion projecting below its heel portion and below the horseshoe carried by the pad so as to first engage the ground.

5. 2. The combination with a horseshoe, of a pad of cushioning material having a marginal portion to support the shoe, a heel portion projecting below the surface of the marginal portion, a ledge portion extending forwardly from the heel portion and also projecting below the surface of the marginal portion, and a plate set on edge and secured to said ledge so the toe of the plate is supported below the surface of the pad and projects therefrom to a greater height than the heel of the plate.

3. The combination with a horseshoe, of a horseshoe pad having a marginal portion adapted to support the horseshoe, a heel portion extending below the surface of said marginal portion, and a ledge portion positioned forwardly of the heel portion and also extending below the surface of said marginal portion, and a ground-engaging plate set on edge and secured to said ledge portion to be normally supported spaced below the surface of the marginal portion of the pad and projecting to a height greater than any portion of the pad or the horseshoe carried thereby.

4. The combination with a horseshoe, of a horseshoe pad of cushioning material having a flat marginal horseshoe supporting portion, an integrally formed heel portion projecting to a greater height than the marginal portion, and a loop-shaped ledge extending forwardly from the heel portion, and a metal plate set on edge surrounding said ledge and secured thereto to be supported thereby spaced below the surface of the pad at the toe to project to a greater height than at the heel of the plate and to a greater height than the horseshoe supported

by the pad.

5. The combination with a horseshoe, of a horseshoe pad of cushioning material having a flat marginal portion to support the horseshoe, an integrally formed heel portion and a ledge portion positioned forwardly of the heel portion, each projecting below the flat horseshoe supporting portion, and a metal plate set on edge and secured to said ledge portion to be supported at the toe spaced below the flat marginal portion of the pad and so that the toe of the plate projects a greater distance below said marginal portion of the pad than the heel of the plate or the heel portion of the pad or the horseshoe supported by the pad.

6. In combination with a horseshoe, a horseshoe pad of cushioning material having a flat marginal base provided with an integrally formed heel portion which extends below said base and a ledge portion which extends forwardly from the heel portion and also extends below said base, and a metal plate surrounding said ledge portion, said plate provided with a base flange and set on edge with said flange adjacent to the base of the pad and secured to said ledge to be supported thereby spaced below the base of the pad at the toe so that the toe of the plate extends below the base of the pad to a greater distance than the heel of the plate or the heel of the pad or the horseshoe supported by the pad whereby said toe of the plate first strikes the ground causing the plate to tilt upon compression of the ledge to bring the heel of the plate into contact with the ground, said ledge being compressible to yield to permit the flange of the plate to engage the base of the pad.

In testimony whereof, I sign this specification.

GEORGE J. HEYMOSS, JR.
